Primary Examiner—Stella Reid**[57] CLAIM**

The ornamental design for a connector for an ileostomy or colostomy bag, as shown.

DESCRIPTION

FIG. 1 is a perspective view of a connector for an ileostomy or colostomy bag, showing my new design; FIG. 2 is a top plan view thereof; FIG. 3 is a front elevational view thereof, the rear elevational view being identical; FIG. 4 is a left side elevational view thereof, the right side elevational view being identical; and FIG. 5 is a bottom plan view thereof.

FIG. 1

FIG. 3

FIG. 2

FIG. 5

FIG. 4
